LEWIS R. MCCLATCHIE, OF WESTON, ONTARIO, CANADA, ASSIGNOR TO THE MOFFAT
STOVE COMPANY OF WESTON, LIMITED, OF WESTON, ONTARIO, CANADA.

ELECTRIC HEATING ELEMENT.

1,195,828.

Specification of Letters Patent. Patented Aug. 22, 1916.

Application filed March 4, 1916. Serial No. 82,214.

To all whom it may concern:

Be it known that I, LEWIS ROY MCCLATCHIE, of the town of Weston, in the county of York, Province of Ontario, Canada, a subject of the King of Great Britain, have invented certain new and useful Improvements in Electric Heating Elements, of which the following is a specification.

This invention relates to heating elements 10 of a type particularly adapted for heating pots, kettles, pans and the like which are set over the element. To secure economy it is necessary that the heat generated be taken up as completely as possible by the pot or 15 pan and to as small an extent as possible by the support of the resistance of the element. The ideal in efficiency is hard to attain as the support must completely shield the element from below to prevent losses by downward radiation, and when the element rests 20 on the support the conduction losses are considerable.

I secure the maximum of efficiency compatible with reasonable cost of construction by employing as a support a grooved porcelain slab, the bottoms of the grooves being crossed by a series of integral ribs, preferably convex in cross section and curved to merge in the sides of the grooves.

25 The invention is hereinafter more specifically described and is illustrated in the accompanying drawings in which—

Figure 1 is a plan view of my improved element partly broken away; Fig. 2 a vertical section of the same; and Fig. 3 a cross section of part of the insulating slab illustrating more particularly the configuration of the ribs therein.

In the drawings like numerals of reference 40 indicate corresponding parts in the different figures.

1 is a metal tray on which is supported the rectangular frame 2 of insulating material on which the resistance 3 is strung and through which the connecting wires are led. Within the frame work a porcelain slab 4 is fitted, which rests on the corners 5 of the depending portion 6 of the metal tray. On the bottom of the portion 6 on the 45 pressed up knobs 7 a sheet of asbestos or mineral wool or other heat insulating material is supported, separated by an air space from the slab 4 and by another air space from the bottom of the pan. On top of the 50 frame 2 the metal rim 8 is supported and is

secured to the tray 1 by suitable bolts. The parts hereinbefore described are old in the art, and my invention relates particularly to the construction and arrangement of the slab 4. This slab is formed with a series of 60 grooves 9 in which the coils of the resistance lie. These grooves are semi-circular in cross section at their bottoms, the radius of the semi-circle being somewhat greater than that of the coils of the resistance. Along the bottom of each groove is formed a series of transverse ribs 10. These ribs are curved and have their outer ends gradually merging in the sides of the grooves 9. In cross section each rib is convex so as to reduce 65 as much as possible the contact thereof with the coils of the resistance. It will be noted on reference to Fig. 3 that the curve of these ribs is such that the coils of the resistance tend to lie in the groove resting on the ribs 70 with their sides out of contact with the sides of the grooves. The coils of the resistance are thus completely separated and insulated from one another by the material of the slab between the grooves and at the 75 same time air may pass freely all around the coils. With this construction the amount of heat from the resistance which passes to the slab is materially reduced, owing to the small contact of the metal with the slab 80 and the free air space which is provided around the coils, which allows heat which was formerly wasted to be used in heating air to pass upwardly to exert a heating effect on the pot or pan placed over the 85 element.

It will be understood, of course, that I do not desire to restrict myself to the specific arrangement of the ribs 10, as their construction may be considerably varied and 90 the same result obtained.

What I claim as my invention is:

1. In an electric heating element, a support for the resistance comprising a substantially solid slab of insulating material 100 having a plurality of grooves formed therein closed below and open above, each groove having a series of closely spaced transverse ribs formed at the bottom and raised slightly above the general level of the bottom, in 105 combination with a helical resistance coil laid in said grooves.

2. In an electric heating element, a support for the resistance comprising a slab 110 of insulating material having a plurality

of grooves formed therein, each groove having a series of transverse ribs formed at the bottom, each rib being convex in cross section to reduce its area of contact with the resistance.

3. In an electric heating element, a support for the resistance coils comprising a slab of insulating material having a plurality of grooves formed therein, each groove having a series of transverse ribs formed at the bottom, each rib being curved substantially on an arc of a circle having a radius slightly greater than the radius of the coils of the resistance.

15. 4. In an electric heating element, a support for the resistance coils comprising a

slab of insulating material having a plurality of grooves formed therein, each groove having a series of transverse ribs formed at the bottom, each rib being curved substantially on an arc of a circle having a radius slightly greater than the radius of the coils of the resistance, and each rib being convex in cross section to reduce its area of contact with the resistance. 20

Signed at Toronto Canada this 28th day of February, 1916, in the presence of the two undersigned witnesses.

LEWIS R. McCLATCHIE.
